CAN OPENER

George G. Perkins, Lynn, Mass.

Application February 18, 1946, Serial No. 648,329

5 Claims. (Cl. 30—22)

1

This invention relates to a can opener for use in removing the tops of tin cans which are made in the usual manner with a rolled bead.

It is an object of the invention to provide a can opener which is simple and rugged in structure, which is easy to manipulate, which can be made inexpensively, and which can be used to remove the top of a can, leaving a smooth cut free from any jagged edges.

As hereinafter described in detail, the invention can be embodied in an opener made of strip steel or other suitable material which is suitably shaped and to which is rigidly attached a blade and a fulcrum pin.

For a more complete understanding of the invention, reference may be had to the following description thereof and to the drawing, of which:

Figure 1 is a perspective view of a can opener embodying the invention;

Figure 2 is a fragmentary elevation of the head portion of the opener and part of the handle portion;

Figure 3 is a side edge view of the same;

Figure 4 is a section on the line 4—4 of Figure 2;

Figure 5 is a fragmentary elevation of the upper portion of a tin can showing the opener in position to commence the opening operation;

Figure 6 is a view similar to Figure 5 but showing the opener in the position assumed after the first cut has been made;

Figure 7 is a section on the line 7—7 of Figure 5;

Figure 8 is a section on the line 8—8 of Figure 6.

The opener shown on the drawing is preferably made of strip steel stock of considerable rigidity and preferably of the order of $\frac{1}{16}$ of an inch in thickness. The width of the strip stock may be $\frac{3}{4}$ of an inch or any other width suitable for the purpose. As shown, the opener comprises a head portion 10 and a handle portion 12. The latter may be transversely bent for a considerable portion of its length to provide a more comfortable grip. If desired, a suitable notch 14 may be formed in one side edge of the handle portion, this notch being shaped in such a way as to form a hook 16 adapted for use in removing crown caps of bottles. For convenience in manipulation, the strip is bent as at 18 between the head portion 10 and the handle portion 12 so that the latter extends at an oblique angle from the head portion as indicated in Figure 7.

The extreme end of the head portion is preferably rounded as at 20, the contour being approxi-

2

mately that of a semi-circle. Parallel with this end portion is a blade 22 which is rigidly secured along its upper margin to the rear wall 24 of the head portion by rivets 26 or other equivalent means. A spacing element 28 is mounted between the blade 22 and the rear wall 24 so that the lower portion of the blade is spaced from the rear wall by a distance just sufficient to receive the upstanding rolled bead at the top of a tin can. As indicated in Figure 7, the conventional structure of a tin can such as is commonly used for food stuffs includes a cylindrical wall 30 and a top 32. The top 32 is below the level of the extreme upper edge of the side wall 30 and its peripheral margin is rolled over the upper rim of the wall 30 so as to form a rolled bead 34 as shown. This bead is tightly clamped on the upper rim of the side wall 30 and is usually reinforced by solder to seal the seam formed by the rolled bead.

The rear wall 24 of the head portion of the opener is preferably given a curvature, as indicated in Figure 3, sufficient to conform approximately to the curvature of a tin can of ordinary size. The blade 22 is also given a similar curvature so that a portion of the rolled bead 34 can be received between the wall 24 and the blade 22 as indicated in Figures 5 and 7. The contour of the blade 22 is preferably similar to the contour of the end portion of the wall 24 but may be a little shorter as indicated in Figure 4, the bottom edges of the blade and wall being bevelled in the same direction as therein shown. The rear end of the blade 22 is preferably a straight transverse edge 36 which forms with the bottom or cutting edge of the blade a sharp corner 38 which is employed to pierce the top 32 of the can when the opening operation is begun.

Projecting from the front face of the wall 24 is a fulcrum pin 40. This pin is preferably knurled as indicated and is seated near the lower edge of the head portion 10. It is offset rearwardly from the blade 38 by a distance somewhat less than the height of the rolled bead 34. Thus, when the opener is mounted on the can in the position shown in Figures 5 and 7, the pin 40 engages under the shoulder formed by the lower edge of the outer portion of the rolled bead 34 and the blade 22 projects below the top of the bead and bears against the inside portion thereof. In order to mount the opener in this position, the handle 12 is swung out at an angle of 45° from the side wall 30 of the can. The opener is then pressed down upon the rolled bead 34 so that the bead enters the clearance between the pin 40

and the adjacent blade edge 36. The handle is then swung down to the position shown in Figure 7 whereupon the fulcrum 40 engages under the outer portion of the rolled bead 34. The opener is then in position to start the opening operation. This operation is started by swinging the handle in the direction indicated by the arrow in Figure 5. The opener rocks about the pin 40 as a fulcrum to the position shown in Figure 6. Since the blade corner 38 is very close to the top 32 of the can when the opener is in its initial position, as illustrated in Figure 5, this rocking movement forces the blade corner 38 through the top 32 at a point closely adjacent to the inner surface of the rolled bead 34. The handle is then rocked downward and hitched along slightly so that the next upward rocking movement will result in an extension of the original cut made by the blade 22. These rocking and hitching movements are repeated until a cut of sufficient length is made. If desired, the entire top 32 within the bead 34 may be cleanly cut out.

I claim:

1. A can opener for tin cans having a rolled bead at the top thereof, said opener having a handle portion and a head portion forming a rigid unit, said head portion comprising a rear wall joined to the handle portion, a blade supported at its upper margin by said rear wall and spaced from said wall to receive the thickness of said bead therebetween, a fixed fulcrum pin on the front face of said wall near the lower edge thereof, said pin being offset toward the handle from the blade by a distance slightly less than the height of said exterior bead, the lower edge of the blade being approximately in line with the lower side of the pin.

2. A can opener for tin cans having a rolled bead at the top thereof, said opener having a handle portion and a head portion forming a rigid unit, said head portion comprising a rear wall joined to the handle and curved to conform approximately to the curvature of a can wall and a blade supported at its upper margin by said rear wall and spaced from said wall to receive the thickness of said bead therebetween, the lower edge of said blade being the cutting edge, and a knurled fulcrum pin on the front face of said rear wall above the level of the lower edge of said blade and offset from said blade toward said handle by a distance slightly less than the height of said bead.

3. A can opener for a can having a rolled bead at the top thereof, said opener comprising a rigid metal strip rounded at one end, a rigid blade having a contour similar to that of the terminal portion adjacent to the rounded end rigidly secured at its upper margin to said strip in parallel relation thereto and spaced therefrom by a distance slightly greater than the thickness of said rolled bead, the lower edge of said blade being the cutting edge, and a fulcrum pin secured to said strip near the lower edge thereof and laterally offset from said blade by a distance slightly less than the height of said rolled bead.

15 4. A can opener for tin cans having a rolled bead at the top thereof, said opener comprising a rigid metal strip having a head portion longitudinally curved to conform approximately to the curvature of a can wall and a rigid blade joined at its upper margin to said head portion and spaced therefrom by a distance slightly greater than the thickness of said rolled bead, the lower edge of the blade being the cutting edge, and a fulcrum pin mounted on said strip near a side edge of said blade and above said cutting edge.

25 5. A can opener for a can having a rolled bead at the top thereof, said opener having a handle portion and a head portion forming a rigid unit, said head portion comprising a rear wall joined to the handle portion, a blade parallel to and spaced from said rear wall, and means rigidly connecting said blade and rear wall near their upper edges, and a fulcrum element secured to said rear wall near the lower edge thereof and located so that its lowermost point is substantially flush with the lower edge of the blade.

GEORGE G. PERKINS.
